UNITED STATES PATENT OFFICE.

OLAF HOSTAD, OF DETROIT, MICHIGAN.

SHOE-CLEANING MACHINE.

1,307,670.

Specification of Letters Patent. Patented June 24, 1919.

Application filed July 24, 1917, Serial No. 182,518. Renewed November 21, 1918. Serial No. 263,632.

To all whom it may concern:

Be it known that I, OLAF HOSTAD, a citizen of the United States, residing at Detroit, in the county of Wayne and State 5 of Michigan, have invented certain new and useful Improvements in Shoe-Cleaning Machines, of which the following is a specification.

This invention relates to an improved shoe 10 cleaning machine and has as its primary object to provide a device of this character which may be arranged adjacent the front door of a dwelling, a public building of other similar location and operable by a 15 manually controlled motor so that any person may, before entering the dwelling or building, easily and quickly clean his shoes of all foreign matter to thus prevent the carrying of dirt or disease germs into the 20 dwelling or building.

The invention has as a further object to provide a device of the above described character which may be arranged beneath a porch floor having a trap door opening 25 therein with the device controlled by a conveniently located push-button so that a person standing on the porch may project first one shoe and then the other through the trap door opening between the coacting 30 brushes of the machine to be cleaned.

The invention has a still further object to provide an arrangement employing rotatable brushes arranged to coact with opposite sides of a shoe and wherein the 35 brushes will be yieldably mounted to thus compensate for the variations in width of different size shoes.

And the invention has a still further 40 object to provide a construction wherein a disinfectant will be automatically applied to the cleaning brushes.

Other and incidental objects will appear 45 as the description proceeds and in the drawings wherein I have illustrated the preferred embodiment of the invention and wherein similar reference characters designate corresponding parts throughout the several views:

Figure 1 is a longitudinal sectional view 50 showing the manner in which my improved device may be mounted beneath a porch floor and illustrating the arrangement of the complementary sets of cleaning brushes employed,

Fig. 2 is a plan view of the machine particularly showing the manner in which the

brushes of each set are connected for simultaneous adjustment,

Fig. 3 is a fragmentary sectional view particularly showing the mounting of the 60 cleaning brushes,

Fig. 4 is a fragmentary sectional view showing the type of bracket employed for supporting the outer ends of the tubular arms receiving the shafts for the cleaning 65 brushes,

Fig. 5 is a detail perspective view showing one of the brush supporting arms detached,

Fig. 6 is a fragmentary perspective view 70 particularly illustrating the piping system employed for supplying antiseptic to the cleaning combs for the brushes of the device, and

Fig. 7 is a bottom plan view of the sliding 75 door of the housing for the machine and illustrating the rods employed for supporting the said door.

As previously intimated, my improved machine is preferably mounted beneath a 80 porch floor adjacent the front door of a dwelling or building and for convenience such a floor has been conventionally illustrated in the drawings at 10. A portion of this floor forms the upper side of a housing 11 for the machine. This housing may be of any approved character. Formed through the porch floor at a point substantially midway between the end walls of the housing is a door opening 12 normally closed 85 by a suitable door 13.

Arranged within the housing are spaced vertical shafts or posts 14 connected at their lower extremities with the bottom wall of the housing by socket plates 15 and at their 95 upper extremities to the porch floor by similar socket plates 16. Formed on the posts 14 are annular collars 17 and mounted upon these collars are complementary brush supporting plates 18 which are preferably 100 circular. Connected to the lower side of the said plates are beveled gears 19 secured to the said plates by a plurality of bolts or other suitable fastening devices 20 and mounted upon the upper sides of the 105 plates are hubs 21 which are also secured by the said bolts. As particularly shown in Fig. 3 of the drawings, the posts 14 extend freely through the plates 18, beveled gears 19 and hubs 21 and interposed between the said beveled gears and collars 17 110 are thrust bearings 22 of approved design,

Similar thrust bearings 23 are also interposed between the upper ends of the hubs 21 and the socket plates 16. These thrust bearings of the respective posts will accordingly coact to rotatably support the plates 18.

Screwthreaded at their inner extremities into the hubs 21 of the plates 18 are a plurality of tubular arms 24, as shown in detail in Fig. 5 of the drawings. These arms are arranged at quadrantly spaced points about the hubs to extend radially therefrom and at their outer extremities are detachably received by brackets 25 of the type shown in detail in Fig. 4 of the drawings. The brackets 25 are bolted or otherwise secured to the outer margins of the plates 18 and engage with flat faces 26 formed on the outer extremities of the arms 24 for rigidly holding the said arms against rotation to become disconnected from the hubs 21. Slidably fitted within the arms 24 are a plurality of brush carrying shafts 27 projecting radially with respect to the plates 18. The shafts of the respective plates carry, at their outer ends, complemental sets of brushes, the sets of brushes being, for convenience, indicated at 28 and 29 respectively. These brushes each include a suitable brush head 30 to which the shaft carrying the brush is fixed with the bristles of the brush head extending outwardly therefrom away from the shaft. Fitted in the inner extremities of the arms 24 and bearing between the hubs 21 and the inner ends of the shafts 27 are springs 31 of approved design acting upon the shafts for normally urging the brushes outwardly with respect to the supporting plates 18.

Mounted upon the supporting plates 18 beneath the inner extremities of the arms 24 thereof are a plurality of tangentially arranged brush coupling shafts 32. These shafts are rotatably supported at their extremities by suitable bearings 33 upstanding from the said plates and keyed or otherwise secured to the ends of the said shafts are co-acting beveled gears 34 so that when one shaft of either plate is rotated, the other shafts of the said plate will also be rotated. Mounted upon the shafts 32 at points substantially midway between the ends thereof are, as particularly shown in Fig. 3, pinions 35 provided with blanks 36. These pinions project freely through suitable slots 37 in the lower sides of the arms 24 at their outer extremities and engage with racks 38 upon the lower sides of the brush carrying arms 27. At their inner ends the racks 38 are formed with blanks 39. The pinions 35 are each so proportioned that one revolution thereof will move the brush carrying shaft coacting with the said pinion its full throw with the blank 39 of the said shaft adapted to engage with the blank 36 of the pinion 65 for holding the shaft against outward dis-

placement. As will now be seen from the preceding description, inward movement of any one of the brushes of the complemental sets will cause a corresponding inward movement of the other brushes of that set with the brushes held at the limit of their outward movement by the springs 31. Furthermore, it will be noted upon reference to Fig. 1, that the complemental sets of brushes 28 and 29 are arranged to rotate in a common plane with corresponding pairs of brushes of the said sets adapted to closely approach each other beneath the trap door opening 12 in the porch floor 10.

Mounted within the housing 11 and arranged in alinement with the posts 14 are spaced upstanding bearing brackets 40 and journaled between these brackets is a cylindrical brush 41 of approved character which extends horizontally beneath the trap door opening 12 in the porch floor 10 and touches the plane of rotary movement of the complemental sets of brushes 28 and 29. Fixed upon the ends of the shaft for the brush 41 are beveled pinions 42 and 43 respectively meshing with the beveled gears 19 of the brush supporting plates 18 and connecting the said plates for simultaneous rotary movement. As a means for driving my improved machine, I preferably employ an electric motor such as conventionally illustrated at 44. This motor is mounted upon the bottom wall of the housing 11 and the drive shaft thereof is equipped with a beveled pinion 45 meshing with the pinion 43 of the shaft of the brush 41. Consequently, this motor will simultaneously rotate the brush 41 and, as will be readily understood, also simultaneously rotate the complemental sets of brushes 28 and 29. The motor 44 may be wired to receive current from any suitable source of electrical energy and interposed in the circuit of the said motor is a suitable switch 46 conveniently located to the door opening 12, such as upon the front door frame of the dwelling or building equipped with my improved device. Accordingly, a person standing upon the porch floor 10 may, by opening the door 13, project first one shoe and then the other through the door opening 12 with the sole of the shoe in contact with the brush 41. By operating the switch 46, the brushes of the machine will then be rotated as previously described with the brush 41 acting to clean the sole of the shoe and with the complemental sets of brushes 28 and 29 acting to clean the sides of the shoe. The shoes may thus be readily freed of any dirt before the person enters the dwelling or building and in this connection attention is directed to the fact that the complemental sets of brushes 28 and 29 will automatically adjust themselves to the varying width of different size shoes so that a narrow shoe may be cleaned with the same 130

facility as a wide shoe. Furthermore, by connecting the several brushes of each set for simultaneous sliding movement, a greater rigidity will be imparted to the said brushes for withstanding the shock of contact with the shoe and accordingly tending to permit of a uniform rotary movement of the said brushes.

is rotated.

25 Leading from a suitable disinfectant supply tank preferably arranged within the building or dwelling equipped with the present invention, is a pipe 50 connected with a valve 51 mounted within the housing 11 adjacent the outer side of the door opening.

30 12. The valve 51 is provided with a stem 52 rotatable for closing the said valve and mounted upon the said stem is a disk 53 from which projects spaced pins 54 and 55. Leading from opposite sides of the valve

35 35 along the adjacent side wall of the housing are pipes 56 having angularly disposed and upwardly inclined portions 57 connected with the end walls of the housing and terminating at points above the cleaning combs.

40 47. Connected to the outer terminal of the said pipes are spreaders 58. These spreaders are preferably in the nature of brushes and are arranged above the teeth of the cleaning combs to engage with the uppermost of the

45 said teeth. Extending downwardly from the valve 51 is a pipe 59 which is carried transversely across the bottom wall of the housing and thence provided with an upstanding terminal portion 60 arranged at the outer 50 side of the cleaning comb 49. Connected to the upper extremity of the said terminal portion of this pipe is a spreader 61 similar to the spreaders 58 and arranged to contact with the uppermost of the teeth of the said 55 comb.

Connected to the lower side of the door 13 to extend transversely thereof, are spaced supporting rods 62. These supporting rods are offset at their inner extremities so that 60 the free ends of the said rods are arranged to move beneath the floor 10 and slidably receiving the said rods are suitable loops 63 connected to the floor. The door 13 will thus be slidably supported by the said rods and 65 connected to the lower side of the door to

engage the side edges of the door opening 12, are inwardly extending blocks 64 adapted to direct the door in its movement. Connected to the door 13 to project inwardly therefrom is a substantially V-shaped 70 bracket 65. This bracket is advanced to co-

bracket 65. This bracket is arranged to co-operate with the pins 54 and 55 of the valve disk 53. Consequently, when the door is in the open position, the said bracket

removed to open position, the said bracket will be caused to engage the pin 54 of the valve disk for rotating the said disk and consequently opening the valve 51. Therefore,

sequently opening the valve 51. Therefore, when the device is in use and the door is open, disinfectant will automatically be permitted to flow from the supply tank therefor 80

mitted to flow from the supply tank therefore to the spreaders 58 and 61 which will act to distribute the said disinfectant to the cleaning combs 47 and 49. The disinfectant

cleaning combs 41 and 42. The disinfectant will thus be deposited directly upon the brushes of the machine as the said brushes are rotated, whence the said disinfectant

are rotated, whence the said disinfectant will then be carried to the shoe being cleaned for preventing the carrying of disease germs thereon into the building or dwelling. Upon

thereon into the said ring, and when the closing of the door 13 the bracket 65 will be moved to engage the pin 55 of the valve disk for consequently rotating the said disk

and closing the valve 51. The flow of the disinfectant to the cleaning combs for the brushes will thus be shut off immediately at 95

the time the door 13 of the housing of the machine is closed. In this connection, it will be observed that the disinfectant within

the portions 57 of the pipes 56 will, owing to the inclination of the said portions of the pipes, cease to flow immediately at the time the water of the tank 1 is shut off at the

the flow of disinfectant is shut off at the valve 51. In like manner, the disinfectant within the upstanding terminal portion 60 of the pipe 59 will cease to flow immediately 10

of the pipe 59 will cease to flow immediately upon the closing of the valve. This arrangement therefore provides a construction whereby waste of the disinfectant will be

whereby waste of the disinfectant will be prevented.

a particularly efficient construction for the purposes set forth and while I have indicated that the machine is preferably mounted beneath the porch floor of a building still, I

neath the porch roof of a building still - 1
do not wish to be limited to this construction
as it will be seen that the device may be
otherwise located at any place found con-

Having thus described the invention, what is claimed as new is:

1. A device of the character described including spaced supporting posts, brush carrying plates rotatably mounted thereon, complementary brushes carried by the said plates and rotatable in a common plane by the said plates, a rotatable shaft mounted below the plane of movement of the said first mentioned brushes and connecting the said plates for simultaneous movement, and a brush mounted upon the said shaft to 125 130

rotate therewith and touching the said plane.

2. A device of the character described including spaced supporting posts, brush carrying plates mounted thereon, a plurality of tubular radial arms carried by the said plates, shafts slidably mounted in said arms, complementary sets of brushes carried by the said shafts, tangential shafts mounted upon the said plates, the tangential shafts of respective plates being connected for simultaneous rotation, pinions carried by the said tangential shafts and engaging the said first mentioned shafts for connecting the brushes of each set for simultaneous sliding movement, and means connecting the said plates for simultaneous rotation.

3. A device of the character described including supporting posts, brush carrying plates rotatably mounted thereon, beveled gears carried by the said plates, complementary brushes mounted upon the plates to be rotated in a common plane thereby, a horizontal brush mounted to rotate below the plane of movement of said first mentioned brushes and touch the said plane, and pinions carried by the shaft of said last mentioned brush and engaging the said gears for connecting the said plates for simultaneous rotation.

4. A device of the character described including a housing, a door normally closing the housing, complementary cleaning brushes arranged within the housing and rotatable beneath the said door, means extending within the housing for supplying a disinfectant to the said brushes, and means upon the door to coöperate with said first mentioned means for controlling the flow of the disinfectant.

5. A device of the character described including a housing, a door normally closing the housing, complementary cleaning brushes rotatable within the housing beneath the said door, pipes extending within the housing for supplying a disinfectant to the said brushes, a valve for closing the said pipes, and means carried by the door to coöperate with said valve for opening or closing the valve upon a corresponding movement of the door.

6. A device of the character described including a housing, a door normally closing

the housing, a cleaning brush rotatable within the housing beneath the door, means extending within the housing for supplying a disinfectant to the said brush and having a valve interposed therein, a disk mounted upon the stem of the said valve, spaced pins carried by the said disk, and means mounted upon the door to selectively coöperate with said pins for rotating the disk and opening or closing the valve upon a corresponding movement of the door.

7. A device of the character described including a housing, a door therefor, guide rods carried by the door and operatively connected with the housing for slidably supporting the door to normally close the housing, a cleaning brush rotatable within the housing beneath the said door, means extending within the housing for supplying a disinfectant to the said brush, and means upon the door to coöperate with said first mentioned means for controlling the flow of the disinfectant.

8. A device of the character described including a housing, a door normally closing the housing, a cleaning brush rotatable within the housing beneath the said door, a pipe extending within the housing for supplying a disinfectant to the said brush and having its discharge end tilted upwardly, a valve for closing the said pipe, and means carried by the door to coöperate with the said valve for opening or closing the valve upon a corresponding movement of the door, the tilted extremity of the said pipe being adapted to cut off the flow of disinfectant at the discharge end thereof immediately upon the closing of the said valve.

9. A device of the character described including spaced supporting posts, brush carrying plates rotatably mounted thereon, complementary sets of brushes carried by the said plates for rotation in a common plane thereby, and a brush mounted to rotate in a plane at substantially right angles to the plane of movement of the said first mentioned brushes and connecting the said plates for simultaneous rotation, the brushes of said sets being movable radially with respect to the axes of rotation of the said plates across the face of said last mentioned brush.

In testimony whereof I affix my signature. 105
OLAF HOSTAD. [L.S.]
